UNITED STATES PATENT OFFICE

LOUIS F. SEAMES, OF BUFFALO, NEW YORK.

BOTTLE-STOPPER.

1,103,692.

Specification of Letters Patent.

Patented July 14, 1914.

Application filed May 6, 1913. Serial No. 765,757.

To all whom it may concern:

Be it known that I, LOUIS F. SEAMES, a citizen of the United States, residing at Buffalo, in the county of Erie and State of New York, have invented new and useful Improvements in Bottle-Stoppers, of which the following is a specification.

This invention relates to a bottle stopper which is designed to permit a liquid to be readily poured out of the bottle but to prevent or render difficult the introduction of any liquid into the bottle through the neck thereof.

The object of this invention is to provide a bottle stopper of this character which can be produced at comparatively low cost, which can be readily applied to bottles of standard construction, and which will operate effectively to permit the discharge of liquid from the bottle but prevent the admission of liquid into the bottle through the neck thereof while the stopper is in the neck.

In the accompanying drawings: Figure 1 is a vertical section of a bottle equipped with my improved stopper. Fig. 2 is a horizontal section taken in line 2—2, Fig. 1, looking downwardly. Fig. 3 is a horizontal section taken in line 3—3, looking upwardly.

Similar characters of reference indicate corresponding parts throughout the several views.

The bottle shown in the drawings, as an example, for the application of my invention comprises the usual enlarged body 1 and a neck 2 arranged at the top of the body and provided at its upper end with an external collar or enlargement 3 forming a downwardly facing shoulder on the neck. Within the central part of the neck is arranged the outer shell of the bottle stopper which comprises a cylindrical or substantially cylindrical or annular body 4 which fits with its periphery against the bore of the neck of the bottle. At its upper end the body of the outer shell is provided with a horizontal head 5 having a central liquid discharge or opening passage 6. At its lower end the outer shell is provided with a head 7 having a central opening or liquid passageway 8 and a valve seat 9 around the upper edge of said opening.

Within the outer shell is arranged an inner shell comprising a body 22 which is of substantially cylindrical form and sepa-

rated from the body of the outer shell so as to form an intervening annular space between the same. At its upper end the inner shell body is provided with an im- 60 perforate head 10 which is separated from the upper head of the outer shell by an intervening space or passageway. At its lower edge the body of the inner shell is thickened, as shown at 11 and the periphery of this thickened portion bears against the bore of the outer shell body and also bears at its lower end against the lower head. Between said thickened portion and the upper head of the inner shell 70 its body is provided with an annular row of openings 12. Within the inner shell is arranged a valve 13, preferably of spherical form, which is adapted to move toward and from the seat of the lower head for 75 the purpose of closing or opening the passageway 8.

The inner and outer shells, the lower head and the valve are all preferably constructed of porcelain, glass or other vitreous material so as to avoid any deleterious effect upon the liquids which may pass through the stopper and come in contact with the parts thereof. In the preferred manner of constructing the various parts of the bottle 80 stopper the outer shell body and its upper head are molded in one piece, the lower head is molded in another piece and the inner shell body together with its upper head and lower enlargement are molded in the 85 third piece. Upon assembling these parts so that the enlargement of the inner shell engages with the bore of the body of the outer shell, the lower head engages with the bore of the body of the outer shell, and the 90 lower end of the inner shell, and the ball valve is confined within the inner shell. These parts are all heated together at a sufficiently high temperature to vitrify the same and cause the several parts excepting the ball 95 valve to become united by fusion into one common mass. If desired, however, the several elements which go to make up the inner and outer shells of the stopper may be otherwise formed and assembled. After 100 this stopper has been thus completed the same is pushed into the neck of the bottle from the outer end thereof until the periphery of the outer shell fits snugly against the bore of the neck. The joint between 110 the outer shell and the neck of the bottle is rendered tight by constructing the bore of

the neck of slightly inward tapering form, as shown in Fig. 1, so that the outer shell which is of corresponding tapering form will fit the same and become tightly wedged 5 therein. If desired, the outer shell may be additionally fastened in the neck of the bottle by the use of cement of any suitable kind. After the stopper has been inserted in the neck of the bottle a filling 14, prefer- 10 ably constructed of cork, is inserted in the upper end of the neck until it engages with the top of the outer shell and is then cut off flush with the upper end of the neck. This filling may also be secured in the neck of 15 the bottle by cement of any suitable character and the same is provided centrally with an opening or passageway 15 which registers with the opening in the upper head of the outer shell. Fitting over the upper 20 end of the neck and the filling is a cap which comprises an annular body 16 surrounding the collar of the neck, an inwardly turned annular flange 17 arranged at the lower edge of the body 16 and engaging with the 25 shoulder at the lower end of the collar, a horizontal top 18 connected with the upper edge of the body 16 and bearing against the upper edge of the neck and the filling and having a central opening 19 in line 30 with the opening of the filling, and a depending annular flange 20 arranged on the top 18 around the edge of its central opening and engaging with the bore of the opening in the filling. This cap not only pro- 35 duces a finished appearance of the bottle at the upper end of its neck, but the same operates additionally to confine the stopper in the neck and also provides means whereby an advertisement or the name of the manu- 40 facturer of the contents of the bottle may be displayed on the same. Normally the opening 19 in the cap is closed by a plug 21, particularly while shipping the goods. During the operation of pouring the liquid 45 from the bottle after removing the plug, the ball valve rolls forwardly away from its seat to the upper end of the inner shell, thereby permitting the liquid contents of the bottle to flow through the opening 8 in the

lower head and into the inner shell, thence 50 through the openings in the latter into the outer shell and thence through the openings in the head of the outer shell, the filler and the cap and into the receptacle intended to receive the same. Upon again placing the 55 bottle upright the ball valve automatically closes the opening of the lower head in which position the same cannot be reached by a wire or similar instrument with a view of tampering with the bottle and again fill- 60 ing the same illicitly owing to the inner shell forming a baffle for this purpose and producing together with the outer shell a tortuous passage for the liquid from the in- 65 terior to the exterior of the bottle. 65

This bottle stopper has comparatively few parts, all of which are of simple construction and therefore permits of producing the same at a cost which is not prohibitive and enables the same to be used on bottles containing goods which are sold at a reasonable price. Furthermore, this bottle stopper does not require any striking departure from the form of the bottle now in common use nor does it necessitate a material change 70 in the molds or machinery usually employed 75 in making such bottles. 75

I claim as my invention:

The combination of a bottle having a neck and an external collar at its upper end, 80 a stopper body arranged within the neck and having a central passage, a cap having a body surrounding said collar and a top extending across the mouth of the neck and provided with a central opening, and a 85 tubular filling arranged in the neck and engaging its upper end with the underside of the top and its lower end with the upper end of said stopper body and provided with an axial opening in line with the openings 90 of said top and stopper body. 90

Witness my hand this 2nd day of May, 1913.

LOUIS F. SEAMES.
